UNITED STATES PATENT OFFICE.

CHRISTIAN EITLE, OF STUTTGART, GERMANY.

CENTRIFUGAL MACHINE FOR FEEDING GAS-RETORTS.

No. 906,785.

Specification of Letters Patent. Patented Dec. 15, 1908.

Application filed May 15, 1905. Serial No. 260,409.

To all whom it may concern:

Be it known that I, CHRISTIAN EITLE, manufacturer, a subject of the German Emperor, residing in the city of Stuttgart, Kingdom of Würtemberg, part of the German Empire, have invented a certain new and useful Centrifugal Machine for Carrying Granular Material, and particularly for Feeding Gas-Retorts, of which the following is a specification.

The object of this invention is to provide a device for feeding granular substances, and more particularly intended for feeding coal to horizontal retorts of any suitable length, and of suitable cross section, while the essence of my invention consists in the spinning up to a high speed of a fly-wheel, the shaft of which carries fan blades which feed the material to the retort, so that the power stored in the fly-wheel is gradually consumed during the charging of the retorts.

Said invention is fully shown and described in the following specification of which the accompanying drawings form a part, wherein similar letters of reference designate like or equivalent parts wherever found throughout the several views and in which:

Figure 1 is a side-view in central section of my improved feeding apparatus showing the same in position against the mouth of a horizontal gas retort; Fig. 2 is an end view thereof on the line $x-x$ of Fig. 1; Fig. 3 is a sectional view in detail of a three bladed centrifugal fan used in such apparatus; Fig. 4 is a like view of a four bladed fan used for different material; Fig. 5 is a side and Fig. 6 a top view of the regulating spring and actuating hand-wheel by which the speed of the fan is regulated; and Figs. 7, 8 and 9 are views from various points of portions of the feeding chute at the delivery end thereof.

The device consists of a hollow drum a with a suitable fan or blade d mounted upon a shaft b driven by an electric motor c . The shaft of said electric motor, is provided with a friction wheel or disk c' which is pressed against the periphery of the fly-wheel e by means of a spring d , the tension of which is regulated by the hand-wheel m , which when turned to the extreme limit in one direction will wholly withdraw the wheel c' from contact with the fly-wheel.

As shown in the drawing the apparatus is arranged for the feeding of horizontal gas retorts arranged in vertical or horizontal series, and to this end the fan is mounted upon

a suitable carriage A , usually of the form shown which rolls inward and outward upon a rail-carriage B , which in turn runs along in front of the retorts upon a suitable overhead railway C . The carriage is reciprocated in any desired manner, and the centrifugal feeding fan, etc. is raised and lowered by any suitable mechanism, usually by the chain-gear D shown in Fig. 1.

Above the drum a and to the rear of the center thereof is located the feed-hopper g from which the granular material to be fed is dropped down over the deflectors O into the side chambers f of the drum a ; these chambers f have the inwardly curved bottom portions as shown at f' in Fig. 2, and such curved bottoms direct by gravity the annular material into the central fan-chamber, so that the blades of the rapidly revolving fan will throw the material by centrifugal force forward through the fan chute into the ejection nozzle i and thence into the retort G .

As will be hereinafter referred to the fly-wheel of the fan shaft is spun up to the proper speed to fill the particular retort to which the apparatus is attached, and may then be disconnected and will gradually lose its speed as the retort is filled, the fan stopping at the time the retort is charged to the end; that is the principle I prefer to use is that of the spin-wheel motor, although if desired the motor may be in contact with the fly-wheel at all times, but its power is in any event regulated by manipulation of the hand-wheel m .

The coal or other granular material to be fed is of course slowly fed to the fan, so that one granule in its travel will not interfere with another and thus it will be seen that the material is not forced in a mass to the retort as is usually the case.

The spring d which is intended for the regulation of the pressure of the friction disk against the fly wheel, is threaded at its free end and is provided with a hand wheel m , which serves as a nut, and also with a graduated scale, by means of which the pressure in forcing the friction disk against the fly wheel may be exactly controlled.

The lengths of the retorts at present in use, vary between 3 meters (about 9 feet 10 inches) and 6 meters (about 19 feet 8 inches), the shape and size of the cross section of the retorts differ also, so that the amount of charge in proportion to the unit of length is also different. The height of the charge,

that is to say the amount of the charge is dependent upon the pressure by which the friction disk is forced against the fly wheel by means of the adjustable spring and on the 5 level of the ejection nozzle in relation to the retort, a greater charge requiring a greater pressure of the friction disk and a higher level of the ejection nozzle; the length of throw is dependent upon the corresponding 10 speed of the centrifugal wings or blades, a larger throw requiring also a greater speed of the throwing device, and also upon the selection of a corresponding number of wings or blades, the number of blades being reduced in the case of larger lengths of throw 15 and in the case of greater speeds; it has been found, that for retorts of 9 feet 10 inches length 2 blades, and for retorts of 14 feet 9 inches length, 3 blades and for retorts of 19 feet 8 inches length 4 blades are most suitable for producing the desired result.

The momentum imparted to the fly wheel before the feeding is started, is consumed during the feeding operation, the 25 latter taking place, so as to begin from the extreme end of the retort, so as to start from the bottom of the same and the speed of the centrifugal or throwing wings decreasing also proportionally, while the feeding of the 30 retorts is continued.

By the slantingly arranged passages or channels *ff* which serve for the feeding of the coal from the receptacle to the throwing or centrifugal wings and which are connected 35 to the lower part of the centrifugal drum, the effect is produced, of imparting a uniform speed to the material upon its way through the passages in consequence of the change of direction to which the material is submitted, 40 so that the material is fed in uniform quantities through the said passages and is admitted at both sides of the centrifugal wings at their periphery. An additional regulation of the coal fed is furthermore also produced by the fact, that in the case of the employment of less than four wings or blades, 45 that is to say when retorts of more than 9 feet 10 inches length are to be charged, the blades or wings are provided with sector 50 shaped side walls *n n* of corresponding size, by which means the admission of coal on both sides from the channels or passages may be checked more or less for a certain time.

The displaceable front part *i* of the ejection 55 nozzle which is provided with a cover, produces the result of being able to close the retort during the charging operation, so as to avoid the carrying along of cold air and also to prevent the escape of gases.

60 The coal admitted through the channels provided at both sides, which during the throw in consequence of the direction, originally imparted to it, has the tendency of sliding towards the center line, is divided again 65 by the partition *l*, which is mounted in the

interior of the ejection nozzle and the free end of which points in the direction of the centrifugal drum, so that the stream of material is directed towards the walls on either side of the retorts, the material being thus 70 heaped up on both sides, which is of great value for obtaining a satisfactory and advantageous gasification.

The most essential feature of the invention resides in the employment of four, three and 75 two wings or blades, the latter two of which are provided with sector shaped side walls of corresponding size with the different usual lengths of the retorts, in combination with the regulation of the force of pressure of the 80 friction disk of the motor engine or of any other driving member against the fly wheel of the wings-shaft suitable for the accumulation of large driving forces; and also in combination with inclined channels or passages 85 of varying direction and arranged on both sides for the purpose of the admission of the material, and in combination with the ejection nozzle provided with cover and partition for the closing of the retorts and for the purpose of the piling up of the material in the 90 interior of the retorts on both sides of the same, by which means retorts of any length and of any level of charge may be fed uniformly and under the conditions of storing of 95 material most favorable for the gasification, while the injurious entrance of air or escape of gases are avoided and without any additional mechanical arrangements that would require special driving means.

100 What I claim and desire to secure by Letters Patent of the United States is:—

1. In a device of the class described, a rotating feeder for directing a stream of material by centrifugal force into a receptacle, a 105 motor, mechanism connecting the motor and the rotating feeder, means for disconnecting the motor and the rotating feeder without stopping the rotation, and means for deflecting the stream of material in a horizontal 110 plane toward the side walls of the receptacle.

2. In a device of the class described, a shaft, a fly-wheel carried by the shaft, a motor, a fan or bladed centrifugal feeder mounted upon the shaft, and means for disconnecting the motor from the shaft and fly-wheel 115 without stopping their rotation.

3. In a device of the class described, a shaft, a fly-wheel carried by the shaft, a motor, a fan or bladed centrifugal feeder mounted upon the shaft, means for disconnecting the motor from the shaft and fly-wheel without stopping their rotation, and means for feeding material to the fan at both sides by gravity.

4. In a device of the class described, a fan-chamber, a hopper in communication with the fan-chamber at the bottom and rear, a bladed fan or centrifugal feeder rotating in the fan-chamber, an outlet to the fan-cham- 120 125 130

ber at the bottom and front thereof, a deflector in such outlet for directing the material, a fly-wheel mounted on the fan-shaft, a motor in frictional contact with the fly-wheel, and means for regulating the frictional pressure between such motor and fly-wheel and for disconnecting them without stoppage of rotation.

In witness whereof I have hereunto set my hand in presence of two witnesses.

CHRISTIAN ^{his} X EITLE.
